UNITED STATES PATENT OFFICE.

EDWARD T. SCHOONMAKER, OF NEW YORK, N. Y., ASSIGNEE TO J. S. CONOVER & CO., OF SAME PLACE.

DESIGN FOR A FIRE-PLACE FRONT.

SPECIFICATION forming part of Design No. 15,838, dated February 17, 1885.

Application filed December 5, 1884. Term of patent 7 years.

To all whom it may concern:

Be it known that I, EDWARD T. SCHOONMAKER, of the city, county, and State of New York, have invented a certain new and ornamental Design for Fire-Place Fronts; and the following is declared to be a description of the same.

My design is fully shown in the accompanying photograph.

10 In this design the frame, the basket, the crown-piece, and the fender are especially designed to go together in the production of an artistic effect. The fire-place frame has a plain surface, *a*, a molding, *a'*, and a molding 15 *b* at *b*, and plain bases *c*. The frame between the moldings *a'* and *b* is concave, as at *d*, and the surface is in imitation of hammered or stippled work; and the ornamental raised designs consist of the head at *e*, having designs verging from it upon both sides stem, leaf, and flower designs with dragons' heads. At 20 the upper corners, and connected therewith down the sides, are designs containing flowers, leaves, grapes, ribbons, and medallion-heads, as shown. At *f* in the panel *d* is a design of a burning censer, and leaf and scroll designs upon a draped bar.

The design of the basket consists of the top rail, *g*, bottom rail, *h*, and ends *i*, all having 25 a polished surface. The ends *i* are ornamented with leaf designs, and there is an open panel between these parts, and a round ornamental rod, *k*, spirally twisted, and with molded ends shown.

30 The design of the crown-piece consists of the plain base *l*, the ornamental top molding; *m*, and the imitation oak-leaves at *n*.

The design for the fender consists of the flat polished plate *o*, the surrounding frame having a plain surface, *p*, molded upon its inner 40 and outer edges, the base *r*, the ornamental ogee-molding *s*, having a stippled or hammered background, and raised ornaments of stems and leaves.

The corner-posts *t* are of the ornamental 45 shape shown, and surmounted with acorn-shaped knobs, and there is a polished base-rod, *u*, and balls *u'*, and upper ornamental rods, *v* *v'*. The ornamental front rods, *v'*, terminate in the scroll and ball ornaments at *w*.

In this fire-place front the ornamental design of the frame, grate, crown-piece, and fender harmonize, so as to produce an artistic effect as a whole, the leaf design of the basket ends *i*, the oak-leaf design *n* of the crown-piece, the leaf designs *s*, and scroll designs *u* of the fender all harmonizing with the designs in the frame-panel *d*.

I claim as my invention—

1. In a design for a fire-place front, the ornamental frame consisting of moldings *a'* *b*, bases *c*, the head *e*, and leaves, flowers, stems, and medallions, substantially as shown.

2. The design for the ornamental fire-place front, consisting of the frame, basket, crown-piece, and fender, substantially as described and shown.

Signed by me this 1st day of December, A. D. 1884.

EDWARD T. SCHOONMAKER.
